WATCH

Benjamin S. Katz, Indian Hill Village, Ohio, assignor to The Gruen Watch Company, Cincinnati, Ohio, a corporation of Ohio

Application March 10, 1950, Serial No. 8,471

Term of patent 14 years

(Cl. D42—8)

To all whom it may concern:

Be it known that I, Benjamin S. Katz, a citizen of the United States, residing at Indian Hill Village, in the county of Hamilton and State of Ohio, have invented a new, original, and ornamental Design for a Watch, of which the following is a specification, reference being had to the accompanying drawings, forming a part thereof.

The dominant features of the design reside in those portions shown in full lines.

I claim:

The ornamental design for a watch, substantially as shown and described.

BENJAMIN S. KATZ.
